CLAIM

The ornamental design for a hand flexion restrictor, as shown and described.

DESCRIPTION

FIG. 1 is a front view of a hand flexion restrictor showing my new design;

FIG. 2 is a rear view of the hand flexion restrictor;

FIG. 3 is a right side view of the hand flexion restrictor;

FIG. 4 is a left side view of the hand flexion restrictor;

FIG. 5 is a top view of the hand flexion restrictor;

FIG. 6 is a bottom view of the hand flexion restrictor;

FIG. 7 is a bottom front side perspective view of the hand flexion restrictor; and,

FIG. 8 is a front view of the hand flexion restrictor in use. The broken lines in FIG. 8 are illustrative of environmental structure forming no part of the claimed design.
